UNITED STATES PATENT OFFICE.

CHARLES A. KELSEY, OF SCHENECTADY, NEW YORK, ASSIGNOR TO GENERAL ELECTRIC COMPANY, A CORPORATION OF NEW YORK.

CENTRIFUGAL EXTRACTOR.

Application filed December 10, 1927. Serial No. 239,100.

My invention relates generally to centrifugal extractors and more particularly to an improved construction for continuously feeding material therethrough.

- 5 In centrifugal extractors as heretofore constructed it has been the practice to provide a rotatable perforated receptacle into which liquor containing solid material in suspension was delivered, the liquid being 10 thrown outwardly through the perforations in the receptacle by centrifugal force and the solid material being retained on the inner wall of the receptacle. It was necessary to stop the rotation of these extractors 15 periodically and remove the solid material from the walls of the receptacles which was inconvenient and which decreased the capacity of the extractors over any given period of use.
- 20 It has been proposed to continuously feed material through extractors of this type by various means so that it would be unnecessary to interrupt their operation to remove solid material therefrom, but such arrangements as heretofore proposed have been 25 objectionable because of the excessive amount of power required to operate the extractors when the feeding devices were used. The increase of power required in using these feeding devices has been due largely to the fact 30 that solid material became packed between the feeding elements and the wall of the receptacle. Moreover, in many forms of these devices the power applied to them has been 35 such as to produce a torque directly opposing the means employed for rotating the extractor which further increased the power required.

- The object of my invention is to provide 40 an arrangement for feeding material through the perforated receptacle of a centrifugal extractor of this type such that the power required to operate the feeding mechanism will be minimized, and such that the 45 feeding means will not increase the load on the means for driving the extractor. I accomplish this by providing means for feeding the material through the perforated receptacle, which moves in one direction along 50 a wall of the receptacle and which then moves in another direction along and away from the wall of the receptacle. Such an arrangement feeds the material along the wall 55 of the receptacle during movement of the feeding means in one direction without caus-

ing the material to become packed between the feeding means and the receptacle, and permits the feeding means, during its movement in the other direction, to slide freely over the solid material. In this way force 60 is applied for feeding the material only in the direction of feed without producing any substantial torque resisting the means for driving the extractor and without accumulating packed solid material between the receptacle and the feeding element. 65

My invention will be more fully set forth in the following description referring to the accompanying drawing, and the features of novelty which characterize my invention 70 will be pointed out with particularity in the claims annexed to and forming a part of this specification.

In the drawing Fig. 1 is a vertical, sectional view of a centrifugal extractor embodying my invention; Fig. 2 is a transverse sectional view on the line 2—2 of Fig. 1, and Fig. 3 in a fragmentary section of the extractor, in which the position of the feeding element during its downward movement is indicated in full lines, and in which its position during its upward movement is indicated in dotted lines. 75

Referring to the drawing, I have shown my invention, for convenience in illustration, in connection with a centrifugal extractor comprising a rotatable cylindrical receptacle 10 having a perforated side wall 10^a within which the solid material is retained and through which the liquid is discharged, the openings in the perforated side wall being made small enough to retain the solid material therein. The perforated wall 10^a, which is reenforced by a plurality of bands 10^b so as to withstand centrifugal 80 stresses, is mounted on a base member 10^c of the receptacle provided with outlets 10^d through which solid material separated from the liquor fed into the receptacle is discharged. The receptacle is driven by an 85 electric motor 11 or other suitable means mounted on an overhanging framework 12, and the receptacle is suspended from this framework by a shaft 13 which is driven 90 by the motor. The shaft 13 extends through an opening 10^e in the upper wall of the receptacle and is secured to the base 10^c of the receptacle so as to form a driving connection between the motor 11 and the receptacle. Liquid discharged from the receptacle 95

10 impinges against the wall of a cylindrical chamber 14 arranged about the receptacle and flows into an annular liquid receiving trough 15 formed in the bottom thereof from which it flows through a pipe 16. A wall 15^a of the trough extends about the base 10^c of the receptacle in spaced relation thereto so as to permit the base member to turn freely in the chamber 14. The wall 15^a extends above the openings 10^a in the base 10^c and is inclined toward the openings 10^b so that the solid material discharged from the receptacle is directed by the wall into the hopper 17 arranged below the liquid receiving trough.

When liquor containing solid material, such as crystals or pulp, is fed into the rotating receptacle 10, it is desirable that the liquid should pass through the perforated side wall of the receptacle 10 and that the solid material should gradually move toward the bottom of the receptacle and be discharged through the openings 10^a into the hopper 17. However, it is apparent that unless some arrangement is provided for feeding the pulp or crystals toward the bottom of the receptacle that it will be retained on the side walls of the receptacle by centrifugal force. In accordance with my invention the flow of the material along the wall of the receptacle 10 is controlled by providing a feeding element arranged adjacent the inner wall of the receptacle and moving this element in one direction along the axis of rotation of the receptacle so as to feed the material toward the bottom of the receptacle, and then moving the feeding element toward the top of the receptacle and away from the side wall thereof, so that the material moved downwardly during the first mentioned movement will not be disturbed by the element in returning to its initial position. In the construction illustrated in the drawing, a plurality of such feeding elements 19 are arranged between a hollow reciprocating cylindrical member 20 of somewhat smaller diameter than the inside of the receptacle 10 and the perforated side wall of the receptacle. The feeding elements are arcuate in form and pivotally connected at 19^a to the reciprocating cylindrical member 20 so that upon rotation of the member the feeding elements are thrown outwardly to a substantially horizontal position by centrifugal force. The feeding elements are formed so that when they are in this horizontal position they overlap, as indicated at 19^b, and extend closely adjacent the walls of the receptacle 10 so as to form a series of continuous annular partitions between the member 20 and the receptacle 10. Stops 20^a are arranged above each of the feeding elements so that during downward movement of the member 20 in the receptacle 10 the feeding elements are retained in the posi-

tion in which they are illustrated in Fig. 1 of the drawing, so as to positively feed the solid material, which accumulates on the inner wall of the receptacle, downwardly. Upon upward movement of the member 20 relative to the receptacle 10 the friction between the feeding elements and the material accumulated on the side wall of the receptacle causes the feeding elements to move downwardly about their pivotal supports 19^a and away from the side wall of the receptacle, as shown in dotted lines in Fig. 3, and slide over the inner surface of the solid material against which they are urged by centrifugal force. In this way the feeding elements are moved upwardly to their initial position without disturbing the solid material which has been fed along the inner wall of the receptacle during downward movement of the feeding elements in a horizontal position against the stops 20^a. Although I have shown the feeding elements arranged in series of annular groups in which the feeding elements overlap, they may be arranged in any other convenient manner. The cylindrical member 20 is supported during its reciprocatory movement, which actuates the feeding elements as above described, by a lower bearing 20^b and an upper bearing 20^c which is carried by a transverse imperforate partition wall 20^d formed in the cylindrical member in spaced relation to the upper wall thereof, the lower bearing 20^b being slidably keyed at 13^a to the shaft 13 so that the receptacle and the cylindrical member are rotated together by the motor 11. It is not essential, however, to rotate the cylindrical member 20 with the receptacle 10 and in some instances it may be desired to dispense with the key 13^a and rotate or oscillate the cylindrical member relative to the receptacle by other suitable mechanism. The cylindrical member 20 may be reciprocated in any suitable manner, but in the construction shown it is reciprocated by a gear and crank mechanism including a lever 21, which is pivotally supported at 22 on a bracket 23 carried by the framework 12, and which is driven by a worm 24 secured to the shaft 13 connecting the motor 11 with the receptacle 10. The movement of the lever 21 is transmitted to the cylindrical member 20 so as to reciprocate the same by a roller 25 secured to the lever 21, which is arranged between flanges 26 formed on the hollow shaft 27 extending through the opening 20^e in the upper wall of the member 20 and secured to the imperforate partition wall 20^d formed in the cylindrical member adjacent the upper wall thereof. A supply pipe 18, which is supported in any convenient manner, is arranged to discharge liquor having solid material in suspension through the opening 20^e in the upper wall of the cylindrical member 20 into the space between 130

- the upper wall of the cylindrical member and the imperforate partition 20^a, from which it flows through openings 20^f into the space between the two uppermost of the feeding members 19, the cylindrical member 20 and the perforated wall 10^a of the receptacle. As the openings 20^f are formed in the side wall of the cylindrical member 20 at the upper surface of the imperforate partition 20^a and between the two uppermost feeding elements 19, the solid material and liquor will not be trapped within the cylindrical member 20 and the solid material will not accumulate in the top of the receptacle 10.
- In the operation of the centrifugal extractor which I have described, liquid having solid material in suspension is fed into the cylindrical member 20 and is discharged through the openings 20^f into the space between the cylindrical member and the perforated wall of the receptacle 10. The receptacle and the cylindrical member are rotated at high speed by the electric motor 11 so that the liquid is discharged through the perforations 10^a into the chamber 14 from which it is removed through the pipe 16, and the solid material is retained against the inner wall of the receptacle 10 by centrifugal force. The cylindrical member 20 is rotated with the receptacle 10 by the key 13^a and is reciprocated longitudinally of the receptacle at the same time by the roller 25, which is actuated by the worm 24 driving the link 21 through the gear and crank mechanism supported on the bracket 23. As the cylindrical member 20 is moved downwardly the feeding elements 19 are retained in their horizontal position against the stops 20^a so that the feeding elements move along the inner wall of the receptacle 10 and feed the solid material, which accumulates therein, downwardly. Upon upward movement of the cylindrical member 20 the feeding elements 19 are swung about their pivotal supports 19^a away from the perforated side wall 10^a of the receptacle 10, as indicated in dotted lines in Fig. 3, by the solid material indicated at M which is retained against the perforated wall 10^a of the receptacle by centrifugal force. Although centrifugal force retains the feeding elements against the material on the perforated side wall of the receptacle 10, it does not exert sufficient force to disturb the material during the upward movement of the feeding elements. As the feeding elements are retained against the solid material on the inner wall of the receptacle by centrifugal force during this upward movement of the member 20, upon its downward movement which follows the friction of the feeding elements against the material turns them about their pivotal supports 19^a to a horizontal position into engagement with the stops 20^a and feeds the solid material downwardly, as previously described.
- The centrifugal extractor which I have disclosed is merely illustrative of one embodiment of my invention, and I intend, therefore, in the appended claims to cover all modifications which do not depart from the spirit and scope of my invention.
- What I claim as new and desire to secure by Letters Patent of the United States is:—
1. A centrifugal extractor comprising a receptacle having a perforated side wall, means for rotating said receptacle, a feeding element adjacent the side wall of said receptacle, means for supporting said element, and means for moving said support so that said element moves back and forth along the side wall of said receptacle, said supporting means being arranged so that said element moves away from said side wall when said supporting means is moved in one direction.
  2. A centrifugal extractor comprising a receptacle having a perforated side wall, a member in said receptacle, means for rotating said receptacle, means for reciprocating said member along the axis of rotation of said receptacle, and means pivotally supported on said member responsive to reciprocatory movement of said member for feeding material through said receptacle.
  3. A centrifugal extractor comprising a receptacle having a perforated side wall, means for rotating said receptacle, a member in said receptacle, a feeding element pivotally connected to said member and adapted to be brought closely adjacent the side wall of said receptacle upon rotation of said member, means for reciprocating said member, and means for retaining said element closely adjacent the side wall of said receptacle during its movement in one direction only so as to feed material through said receptacle and to permit said element to swing away from the side wall of said receptacle during movement of said member in the other direction.
  4. A centrifugal extractor comprising a receptacle having a perforated side wall, means for rotating said receptacle, and means for feeding material through said receptacle comprising a member in said receptacle having a plurality of elements pivotally connected thereto which are adapted to be moved closely adjacent and away from the side wall of said receptacle during rotation of said member, said elements being shaped so as to form a continuous annular wall when they are adjacent the side wall of said receptacle.
  5. A centrifugal extractor comprising a receptacle having a perforated side wall, a member in said receptacle, means for rotating said receptacle and said member, means for reciprocating said member longitudinally of the axis of rotation of said receptacle,

and a plurality of feeding elements pivotally connected to said member which are adapted to be moved closely adjacent the side wall of said receptacle in response to rotation of the latter, said elements being shaped so as to overlap and form a continuous annular wall when they are closely adjacent said side wall, and means for retaining said elements closely adjacent the side wall of said receptacle

10 during movement of said member in one direction only so as to feed material through said receptacle and to permit said elements to swing away from the side wall of said receptacle during movement of said member in the other direction.

15 In witness whereof, I have hereunto set my hand this 8th day of December, 1927.

CHARLES A. KELSEY.
